UNITED STATES PATENT OFFICE

2,069,615

PISTON FOR INTERNAL COMBUSTION MOTORS

Elmer C. Long, Grosse Pointe Park, Mich.

Application May 4, 1933, Serial No. 669,316

13 Claims. (Cl. 309—11)

This invention relates to certain improvements in a piston and is a furthering of the invention set forth in my pending application filed September 9, 1932, Serial No. 632,325, for a piston for internal combustion motors the present invention having for one of its objects to provide improved means for supporting the resiliently flexible side of the piston skirt.

Another object of the invention is in providing the skirt of the piston with an improved form of resiliently flexible thrust side.

A further object of the invention is in providing the piston skirt with an improved resiliently flexible thrust side and a yieldable expansible member, active on the thrust side.

A still further object of the invention is in providing the piston skirt on the pin boss sides of an improved construction whereby the pin bosses, when moved outward by expansion of the head, are prevented from being active on one of the thrust sides of the skirt.

Other and further objects will appear in the specification and be specifically pointed out in the appended claims, reference being had to the accompanying drawing, exemplifying the invention, and in which:—

Figure 1 is a pin boss side elevation of this improved piston.

Figure 2 is a longitudinal vertical sectional view taken approximately on the line II—II of Fig. 1.

Figure 3 is a longitudinal vertical sectional view taken approximately on the line III—III of Fig. 2.

Figure 4 is an inverted end view of Fig. 1.

Figure 5 is a horizontal sectional view taken approximately on the line V—V of Fig. 2.

Figure 6 is an inverted horizontal sectional view taken approximately on the line VI—VI of Fig. 3.

Referring by numerals to the accompanying drawing, this improved piston comprises a head 1 having a side wall 2 in which the piston ring recesses 3 are formed, and integral with the side wall 2 of the head, is the piston skirt 4 having a power thrust side 5 and a compression thrust side 6, and disposed between said thrust sides are the pin boss sides 7.

The piston is of the conventional trunk type having a pin boss 8 inwardly extending from each pin boss side 7 which is integral with the side wall 2 of the head, the pin boss sides 7 being relieved on the outside by respective insets 9 formed thereon.

Each pin boss side 7 of the piston skirt is provided with an approximate L-shaped slot 10

which is formed or cut through the thickness of each pin boss side 7, the vertical extension 11 of each slot 10 extending upwardly to the core opening 12 formed above each pin boss and the lower end of each vertical extension 11 joining a respective transverse extension 13 of respective slots 10, said transverse extensions each being formed on the bottom of respective insets 9 and extending to one end of each inset towards the power thrust side 5 of the piston skirt.

The vertical extension 11 of each L-shaped slot 10 is cut into respective pin bosses 8, and each pin boss on one side is cut away from the skirt 4 as designated at 14, as shown more clearly in Fig. 5 adjacent each vertical extension 11 of the slots 10.

Each pin boss side 7 on one end is provided with a longitudinally extending slot 15, each slot 15 paralleling a respective vertical extension 11 of the L-shaped slots 10. Each slot 15 extends from the bottom of respective insets 9, to and into the lower piston ring groove 3, where said slots 15 join a transverse slot 16 which is formed in and cut through the thickness of the piston head wall 2. The transverse slot 16 is joined by a longitudinally extending slot 17 which is disposed intermediate the slots 15 and extends from the lower end of the skirt 4, the formation of the slots 15, 16 and 17 providing a pair of adjacent tongue portions 18 on the compression thrust side 6 of the piston.

The slot 15 and the vertical extension 11 of the L-shaped slots 10 on each pin boss side, by reason of them extending parallel to one another, form a supporting leg 19 on each pin boss side of the piston for the support of the cylinder bearing portion 20 on each pin boss side beneath the transverse extension 13 of respective L-shaped slots 10, said legs also providing supports for the respective tongue portions 18 which are separated from the head by the slot 16 on the compression thrust side 6 of the skirt 4.

Joined at their ends with the power thrust side 5 and the compression side 6 respectively, of the skirt 4, are a pair of members 21 of web formation, said members 21 extending across the interior of the skirt at right-angles to the pin boss axis and being free from engagement with the pin bosses, each member 21 having an intermediate disposed opening 22 of larger diameter 50 than the bearings of the pin bosses 8, said openings being in alignment with said pin bosses.

Formed in each member 21 adjacent a respective tongue portion 18, is an opening 23, said openings being in alignment, and mounted in said

openings is a bolt 24 having its head 25 engaging the outside of one of the members 21. The other end of said bolt 24 is threaded at 26 and has an adjusting nut 27 thereon in engagement with the outside of the other member 21, and mounted on said bolt between the members 21, is a coil spring 28.

Pistons of this character are preferably made of an aluminum alloy having some resiliency and 10 after machining and finishing this improved piston, the bolt 24 having the spring 28 thereon, is adjusted to an engaging length with respect to the members 21 so as to permit the spring 28 to hold the tongue portions 18 yieldably apart 15 such distance that the skirt diameters across the thrust sides and across the lower cylinder bearing portions 20 on the pin boss sides, will be a required fit for the motor cylinder in which the piston is to be mounted.

20 In adjusting the bolt 24, the tightening thereof when pulling the tongue portions 18 towards each other, will also move the opposing portions 20 of the skirt on the pin boss sides inward from points adjacent the power thrust side, and the lower end of each leg 19 by reason of being connected to the lower part of the skirt will also be pulled inward. The members 21 will fulcrum at 29 where they are joined with the power thrust side 5 during adjusting of the bolt 24.

30 When the piston is operating in the cylinder of an internal combustion motor, the tongue portions 18 on the compression thrust side 6 of the piston skirt and the lower portions 20 of the skirt will be permitted to respond to both the expanding pressure of the piston and the cylinder wall pressure, the spring 24 obviously being compressed by the inward cylinder wall pressure, this inward movement of the tongue portions 18 and the portions 20 of the skirt, which is permitted by the 35 spring 28, preventing seizing or scoring of the skirt in the cylinder.

When the cylinder and the piston become cool and the cylinder wall pressure against the skirt is relieved, the spring 28 which has been previously heat tested, will expand outwardly against the ends of the members 21 adjacent the tongue portions 18, thereby causing said tongue portions and the lower portions 20 of the skirt to keep in following contact with the cylinder wall. Obviously the spring 28 will cause the tongue portions 18 and the portions 20 on the pin boss sides to maintain resilient contact with the cylinder wall during changing thermal conditions, and in maintaining this resilient contact with the cylinder wall, it is clear that the power thrust side 5 will also be in contact with the cylinder wall, the skirt of the piston therefore being provided with means whereby both piston-slap and seizing or scoring of the piston is prevented.

60 Inasmuch as the legs 19 depending from the side wall 2 of the head, support the compression thrust side 6 which is separated from the head and the portions 20 on the pin boss sides of the skirt which are separated from the pin boss sides 65 7 by the extension 13 of the L-shaped slot 10, the transverse members 21 merely serve as thrust members or struts to the tongue portions 18 of the compression thrust side 6, in addition to said members 21 serving as fulcrum members for the 70 tongue portions 18.

From the foregoing, it is obvious that the invention provides a piston having a skirt which is resiliently flexible on both the compression thrust side and on the pin boss sides beneath the pin 75 bosses, the resiliently flexible cylinder engaging

area of the skirt therefore, extending approximately two-thirds of the skirt circumference, thus leaving the remaining approximate one-third of the skirt circumference solid, as is afforded by the thrust side 5 being integral with the side 5 wall 2 of the head. As the compression thrust side 6 of the skirt and the connecting cylinder bearing portions 20 maintain engagement with the cylinder wall by reason of the spring 28 on the bolt 24, it necessarily follows that the power 10 thrust side 5 will maintain engagement with the cylinder wall by the cylinder fitting action of the tongue portions 18 of the compression thrust side 6.

As the head of the piston is of smaller diameter 15 than the skirt, expansion of the head across the pin boss diameter, will cause outward expanding movement of the pin bosses 8, but as the compression thrust side 6 and the cylinder bearing portions 20 are free from the pin bosses by the 20 L-shaped slots 10, this outward expanding movement is prevented from becoming active on the compression thrust side, and as the pin boss sides 7 are relieved by the insets 9, the pin boss sides 7 will be prevented from engaging the cylinder 25 wall.

The pin bosses 8 are reinforced by a pair of centrally disposed webs 30 which are formed integral therewith and extend upwardly on the inner periphery of the pin boss sides 7 and across 30 the under side of the head.

The members or struts 21, by reason of each of them having an opening 22 larger than the bearings of the pin bosses 8, do not engage the piston pin of the piston and therefore are free 35 to act on the tongue portions 18 without binding.

It is obvious that various changes may be made in the details of construction without departing from the spirit of this invention, and it is therefore to be understood that this invention is not to be limited to the specific construction shown and described.

What I claim is:—

1. A piston comprising a head, a skirt having opposing thrust sides and pin bosses, said skirt being separated from the head on one of its thrust sides, supporting members extending from one thrust side to the other, and legs formed in the skirt wall and being free from engagement with said pin bosses and depending from the head for the support of said separated thrust side.

2. A piston comprising a head, a skirt having opposing thrust sides and pin bosses, said skirt being separated from the head on one of its thrust sides, supporting members free from engagement with the pin bosses extending from one thrust side to the other, and legs formed in the skirt wall and being free from engagement with said pin bosses and depending from the head for the support of said separated thrust side.

3. A piston comprising a head, a skirt having opposing thrust sides and pin bosses, said skirt being separated from the head on one of its thrust sides, supporting members extending from one thrust side to the other, and legs formed in the skirt wall and being free from engagement with said pin bosses and depending from the head for the support of said separated thrust side, said separated thrust side being longitudinally slotted, and a resiliently yieldable element interposed between said members.

4. A piston comprising a head, a skirt having opposing thrust sides and pin bosses, said skirt being separated from the head on one of its 75

- thrust sides, supporting members free from engagement with the pin bosses extending from one thrust side to the other, and legs formed in the skirt wall and being free from engagement with 5 said pin bosses and depending from the head for the support of said separated thrust side, said separated thrust side being longitudinally slotted, and a resiliently yieldable element interposed between said members.
10. 5. A piston comprising a head, a skirt formed continuous with the head on one side, and separated from the head by a transverse slot on its opposite side, pin bosses integral with the skirt, said separated side of the skirt being longitudinally slotted, transverse members extending from the separated side to the opposite side of the skirt, resilient means interposed between said members adjacent the separated side of the skirt, and legs formed in the skirt depending from the head and being free from engagement with the pin bosses for the support of said separated skirt side.
6. A piston comprising a head having a side wall, a skirt formed continuous with the head on one side, and separated from the head on its opposite side, pin bosses integral with the skirt, said separated side of the skirt being longitudinally slotted, transverse members extending from the separated side to the opposite side of the skirt, resilient means interposed between said members adjacent the separated side of the skirt, and a leg depending from the side wall of the head between respective pin bosses and the separated skirt side.
35. 7. A piston comprising a head having a side wall and a skirt having one of its thrust sides longitudinally slotted and separated from the head and providing adjacent thrust faces, pin bosses, legs separated from said pin bosses depending from the side wall of the head for the support of said thrust faces, and a resiliently yieldable element disposed across said thrust faces and being cooperable to separate said thrust faces.
45. 8. A piston comprising a head having a side wall and a skirt having one of its thrust sides longitudinally slotted and separated from the head and providing adjacent thrust faces, pin bosses, legs depending from the side wall of the head and being separated from the pin bosses and said thrust faces for the support of the thrust faces, an adjustable tie member disposed across said thrust faces and being cooperable therewith, and a resiliently yieldable element 55 mounted on the tie member having its ends disposed to separate said thrust faces.
9. A piston comprising a head having a side wall, a skirt and pin bosses, the skirt having opposing thrust sides, a pair of adjacent tongue portions in one of the thrust sides having parts which extend to the open end of the piston, and a leg extending from the side wall of the head 5 to the lower part of the skirt between each respective tongue portion and a respective pin boss, said legs being free from engagement with the pin bosses and respective tongue portions.
10. A piston comprising a head having a side 10 wall, a skirt and pin bosses, the skirt having opposing thrust sides, a pair of adjacent tongue portions in one of the thrust sides, a leg extending from the side wall of the head to the lower part of the skirt between each respective tongue 15 portion and a respective pin boss, said legs being free from engagement with the pin bosses and respective tongue portions, and a transverse member extending from each tongue portion to the other thrust side of the skirt.
11. A piston comprising a head having a side 20 wall, a skirt and pin bosses, the skirt having opposing thrust sides, a pair of adjacent tongue portions in one of the thrust sides, a leg extending from the side wall of the head to the lower part of the skirt between each respective tongue 25 portion and a respective pin boss, said legs being free from engagement with the pin bosses and respective tongue portions, a transverse member extending from each tongue portion to the other 30 thrust side of the skirt, and a resiliently yieldable element disposed between said members adjacent the tongue portions.
12. A piston comprising a head and a skirt having opposed thrust sides, one of said thrust 35 sides being slotted for flexibility and being separated from the head, pin bosses, legs separated from the pin bosses and said slotted thrust side and depending from the head for the support of said flexible thrust side, and a resiliently yieldable element disposed across said slotted thrust side.
13. A piston having a skirt, pin bosses extending from the skirt and the skirt having opposed thrust sides, a pair of adjacent tongue portions 45 formed in one of the thrust sides, a leg formed in the skirt on one side of each tongue portion and separated therefrom, a transverse member extending from each tongue portion to the other thrust side of the skirt, a resiliently yieldable element 50 disposed between said members adjacent the tongue portions, and an L-shaped slot in the skirt on each pin boss side in opposing relation from each other and disposed so that the horizontal bar of each slot extends beneath 55 a respective pin boss.

ELMER C. LONG.
